UNITED STATES PATENT OFFICE

VAPOR GENERATOR

Howard J. Kerr, Westfield, N. J., assignor to
The Babcock & Wilcox Company, Bayonne,
N. J., a Corporation of New Jersey

Application October 30, 1930. Serial No. 492,131

14 Claims. (Cl. 122—235)

This invention relates to vapor generators including tubular boilers and their furnaces, and more particularly to a refractory wall in such a vapor generator formed in conjunction with the tubes and supported thereby.

An object of the invention is to form a refractory wall in a vapor generator including a tubular boiler and a furnace by securing the refractory material to certain of the tubes.

Another object of the invention is to provide a vapor generator including a tubular boiler and a furnace in which certain curved tubes support a refractory wall.

A further object of the invention is to adapt a row of vapor generating tubes to serve as a protection for the headers in which they are expanded.

Other objects will be apparent to those skilled in this particular art from the description in the specification in connection with the drawings in which—

Fig. 1 is a side view of a portion of a vapor generator partly in section;

Fig. 2 is an enlarged view partly in section of a detail of the invention;

Fig. 3 is an enlarged view in section of a detail of the invention taken along the line 3—3 of Fig. 2;

Fig. 4 is an enlarged view in section of a detail of the invention taken along the line 4—4 of Fig. 2;

Fig. 5 is an enlarged view partly in section of a detail of the invention taken at right angles to Fig. 4;

Fig. 6 is a side view of a portion of a boiler and its furnace illustrating an embodiment of the invention.

One embodiment of the invention is shown in Fig. 1 in which a specific use for the invention is illustrated. Two banks of steam generating tubes 1 are shown expanded in headers 2, 3 and 4; the headers 3 and 4 being located inside a boiler above a furnace 5. Steam generating tube 6 are located in the upper part of the furnace below the tubes 1 and serve as a slag screen therefor; the inner ends of these tubes extend toward the center of the furnace beyond their respective headers 3 and 4 and are bent upwardly and back, and expanded therein; a framework of refractory material is provided to form outer wall 7 and roof 8 for this bent portion of slag screen tubes.

As shown most clearly in Figs. 2 to 5, fins 10 are secured as by welding, to the inner side of 55 the bent portion of the tubes 6 normal to the

plane of the tubes at their point of contact, the fins being generally concentric with the tubes and embracing only a part of their circumference, preferably less than half. By virtue of their location, the distances between the faces of the fins are greater at the edges adjacent the tubes than at their other edges, and hence form pockets of trapezoidal cross-section.

Refractory material, preferably applied while in plastic state, fills the spaces between the tubes and is secured thereto by the fins. As shown most clearly in Fig. 3, the refractory material entirely covers the fins and fills the spaces between the tubes, and with the tubes forms a protective shield for the lower ends of the headers 3 and 4 from the gases of combustion from furnace 5.

It is to be noted that, by reason of the trapezoidal shape of the pockets formed by the fins with their free edges approaching each other, 75 pockets are formed of such shape that they provide an especially effective locking means to hold the refractory material in position.

In the modification shown in Fig. 6, a portion of a boiler furnace is illustrated utilizing 80 rows of curved tubes 20 and 21 as wall tubes. Each row of tubes has fins 22 secured thereto on the concave side, in the manner previously described, and refractory material 23 is held by the fins and forms a refractory backing for the 85 curved tubes. The refractory material is applied to these tubes, preferably while in a plastic state, and is held in place by the fins. Upon hardening this refractory material forms a refractory wall securely anchored to the tubes and 90 effectively supported thereby.

While a specific embodiment of the invention and a definite application have been shown and described, it is to be understood that changes, substitutions, omissions and additions may be 95 made without departing from the spirit of the invention as limited by the appended claims.

What I claim is—

1. In a boiler of the class described, a plurality of banks of steam generating tubes, rows of 100 inside headers for each bank of tubes in the path of hot gases of combustion from the boiler furnace, rows of steam generating tubes adapted to serve as a slag screen for said first named tubes, the ends of said slag screen tubes extending beyond said headers and being bent back and expanded into the lower ends of said headers, a plurality of fins secured to said slag screen tubes in the inner sides of their bent portions, refractory material covering said fins 105 110

and being secured to the tubes thereby; said tubes and refractory material serving as a protection to the bottom of said headers from the hot gases of combustion.

5 2. The method of forming a curved boiler furnace arch wall comprising, forming tubes with projections on corresponding sides, bending each tube so that its adjacent projections form parts of pockets the sides of which are convergent 10 away from the tube, assembling the bent tubes in arch alignment and in such spaced relation that quarters of adjacent tubes form the sides of pockets converging oppositely relative to the convergence of the projections, and positioning 15 plastic refractory material between the oppositely converging pocket sides.

3. In the manufacture of arch walls for boiler furnaces forming metallic projections on tubes, bending each tube so that its adjacent projections form pocket sides converging away from the tubes, assembling the bent tubes in wall alignment, and positioning plastic refractory material between the tubes and the converging 20 projections extending from the tubes.

25 4. In combination, a boiler furnace, boiler sections upwardly inclined from opposite sides of the furnace towards a position intermediate the sides of the furnace, uptake headers at the inner ends of the sections and spaced apart at said 30 positions, sets of downtake headers for the sections located at opposite sides of the furnace, a cross-header below each downtake header, connections between each cross-header and the adjacent set of downtake headers, slag screen tubes 35 leading from each cross-header and extending past the lower ends of the adjacent uptake headers, the slag screen tubes leading from the inner and facing sides of the uptake headers and curved so as to lead around the lower ends 40 of the headers to which they are connected, refractory layers disposed on the back sides of the slag screen tubes and below the uptake headers, so as to cooperate with the tubes in forming shields for the lower ends of the uptake headers, and refractory anchors united 45 with the curved portions of the tubes and converging outwardly thereof.

5. In the manufacture of furnace walls for fluid heat exchange apparatus, forming metallic 50 projections on a tube, bending the tube so that its adjacent projections form pocket sides converging away from the tube, and positioning plastic refractory material between the tube and the converging projections extending from the tube 55 so that the material becomes anchored by the pocket sides.

6. In combination, a boiler furnace, opposed boiler sections including banks of steam generating tubes, upwardly inclined from opposite sides 60 of the furnace towards a high position intermediate the sides of the furnace, uptake headers at the inner ends of the sections and spaced apart at said position, downtake headers for the sections located at opposite sides of the furnace, slag screen tubes leading from positions 65 below the steam generating tubes and extending past the lower ends of the adjacent uptake headers, portions of the slag screen tubes leading from the inner and facing sides of the uptake 70 headers and curved so as to lead around the headers to which they are connected, refractory layers disposed on the back sides of the slag screen tubes and their curved portions, so as to cooperate with the tubes in forming shields 75 preventing direct engagement of furnace gases

with the lower ends of the uptake headers, and refractory anchors integral with the curved portions and converging outwardly of the curved portions.

7. In fluid heat exchange apparatus, a bank of 80 tubes conducting a fluid across a gas pass, slag screen tubes having curved portions provided with projections welded thereto, a header connected to the tubes, and a heat resisting wall interposed relative to the end of the header and oncoming furnace gases and extending around the end of the header, said wall being supported by the curved portions of the slag screen tubes which pass around the lower end of the header and terminate in a connection thereto at the side of the header.

8. In fluid heat exchange apparatus, a bank 85 of tubes conducting a fluid across a gas pass, a header connected to the tubes, and a heat resisting wall interposed relative to the end of the header and oncoming furnace gases and extending around the end of the header, said wall being supported by some of said tubes which pass around the lower end of the header and terminate in a connection thereto at the side of the header.

9. In a manufacture of boiler furnace walls, forming metallic projections on one side only 95 of each of a plurality of tubes, bending each tube toward its side having the projections so that its adjacent projections form pocket sides converging away from the tubes, assembling the bent tubes in wall alignment, and positioning plastic refractory material between the tubes and the 105 converging projections extending from the tubes.

10. In combination, a boiler furnace, boiler sections upwardly inclined from opposite sides of the furnace towards a position above and intermediate the sides of the furnace, uptake headers at the inner ends of the sections and spaced apart at said position, sets of downtake headers for the sections located at opposite sides of the furnace, slag screen tubes connected to the 110 downtake headers and extending across the lower ends of the adjacent uptake headers, portions of the slag screen tubes leading from the inner and facing sides of the uptake headers and curved so as to lead around the lower ends of the headers to which they are connected, a refractory layer disposed on the back sides of the 115 curved portions of the slag screen tubes so as to cooperate with the tubes in forming shields preventing direct engagement of furnace gases with the lower ends of the sides of headers, and refractory anchors extending from the curved portions of the slag screen tubes.

11. In fluid heat exchange apparatus, fluid 125 chambers on opposite sides of a gas pass, a row of tubes connecting said chambers so as to conduct fluid from one to the other across the gas pass, projections on the cooler sides of the tubes, said tubes being bent at their ends near one chamber so as to pass around the lower end of the chamber and to interpose a fluid cooled 130 wall between that chamber and the oncoming gases and to bring the outer ends of said projections nearer together whereby there is provided anchoring means for refractory material 135 disposed along the back sides of the tubes with reference to the approach of the gases.

12. In fluid heat exchange apparatus, opposite 140 fluid chambers, a row of tubes connecting said chambers so as to conduct fluid from one to the other across a gas pass, projections on the cooler 145

sides of the tubes, said tubes being bent at their ends near one chamber to pass around the lower end of the chamber and bring the outer ends of said projections nearer together whereby there is provided anchoring means for refractory material disposed along the back sides of the tubes with reference to the approach of the gases.

13. In fluid heat exchange apparatus, spaced 10 fluid chambers, a furnace, a row of tubes connecting said chambers so as to conduct fluid from one to the other across a gas pass, projections on the remote sides of the tubes with reference to the approach of heating gases, said tubes 15 being bent near their ends and between their connections to said chambers so as to extend around a part of one of the chambers nearest the furnace and provide a fluid cooled wall protecting that part against overheating due to the

oncoming gases and to bring the outer ends of said projections nearer together whereby they provide anchoring means for refractory material disposed along the back sides of the tubes with reference to the approach of the gases.

14. In a boiler of the class described, a bank of steam generating tubes, a row of uptake headers for said bank of tubes in the path of hot gases of combustion, a row of downtake headers connected to the tubes, a row of additional steam generating tubes disposed below and constituting a screen for said bank of tubes, the ends of said additional tubes extending below and beyond the lower ends of the uptake headers and being bent back and expanded in said headers at the lower end thereof, said tubes serving as a protection to the bottom of said headers from the hot gases of combustion.
